INDUCTION COIL WITH SPLIT FLEXIBLE
INSULATING FLANGE

Othmar R. Wuzkowski, Chicago, Ill., assignor to Lindberg Engineering Company, Chicago, Ill., a corporation of Illinois

Filed Nov. 9, 1959, Ser. No. 851,748
3 Claims. (Cl. 336—207)

This invention relates to induction coil and method of making the same and more particularly to the manufacture and construction of large high amperage induction coils for use in billet heaters and the like. Induction coils for billet heaters and similar uses have generally been formed by winding a relatively large copper conductor which is formed with passages therethrough for circulation of cooling water into a helix and inserting arcuate segments of insulating material between the turns of the conductor as it is wound. After winding, the turns are compressed axially and covered or coated with resinous plastic material to serve as an insulating covering and as a binder.

This operation is difficult and laborious since the insulating segments comprising one turn or less must be inserted manually between the turns of the conductor as it is wound. It is very difficult to get the insulating segments placed uniformly in this operation. Furthermore, in coating the assembly with resinous plastic binder it is difficult to get the binder into the coil between the turns thereof, which is desirable to hold the turns together.

It is one of the objects of the present invention to provide an induction coil in which the insulation between turns of the conductor is in the form of a continuous strip wound at the same time as the conductor.

Another object is to provide an induction coil and method of making the same in which the insulation is in the form of an L-section strip having one flange radially underlying the conductor and forming a tubular insulating liner for the coil and its other flange extending radially between adjacent turns of the conductor.

According to a feature of the invention, the radial flange of the insulating strip is slit at spaced points so that when the strip is wound the slits open into V-shaped slots to receive the plastic binder and permit it to penetrate the full thickness of the coil.

The above and other objects and features of the invention will be more readily apparent from the following description when read in connection with the accompanying drawings, in which:

FIGURE 1 is a partial perspective view of a wound coil prior to coating with plastic binder and with the coil cut and shown in section;

FIGURE 2 is a view looking into one of the turns of insulating material in the coil showing the plastic binder in place;

FIGURE 3 is a partial section on the line 3—3 of FIGURE 2;

FIGURE 4 is a diagrammatic view illustrating the winding the coil; and

FIGURE 5 is a sectional view illustrating the step of compressing the turns of the coil.

A completed induction coil, according to the present invention, is formed by an electrical conductor 10, preferably of copper, wound into a tight helix with insulation between adjacent turns and lining the inner surface of the helix. The conductor may be formed in any desired manner, but as illustrated may be a conventional type of construction, including a generally rectangular solid strip 11 to which is pressed or soldered or integrally formed a tubular strip 12 through which cooling water may be circulated during operation of the coil. The exact manner of forming the conductor is not critical to

2

the present invention and it will be understood that any desired type of conductor may be employed.

The turns of the conductor are insulated from each other by means of an insulating strip, indicated generally at 13, which is L-shaped in cross section and which is wound helically with the conductor. The insulating strip includes an axially extending flange 14 which radially underlies the conductor in the completed coil with the turns of the flanges 14 substantially in contact with each other to form a continuous tubular insulating liner for the coil. A second flange 15 of the insulating strip extends radially between adjacent turns of the coil to separate them from each other. In order to permit bending of the flange 15, it is formed throughout its length with spaced slits 16 which will open up as the strip is wound to define V-shaped open slots 17. The flange 15 is preferably of slightly greater width than the conductor so that in the completed coil it will project beyond the conductor as shown.

In forming the coil, the conductor 10 and the insulating strip 13 may be simultaneously wound on a cylindrical mandrel, as indicated in FIGURE 4, over which an insulating sleeve 18 may be fitted, if desired. The conductor and insulating strip are fed simultaneously onto the mandrel in the manner illustrated in FIGURE 4 with the conductor overlying the axial flange 14 of the insulating strip and with the radial flange 15 of the insulating strip being wound between adjacent turns of the conductor. It will be noted that this operation can be performed as a continuous winding operation with no necessity for any manual steps being performed simultaneously with the winding.

As the conductor and insulating strip are wound, the slits 16 in the flange 15 will open up to define the V-shaped slots 17 in the manner more particularly illustrated in FIGURES 1 and 2.

After the conductor and insulating strip have been wound into a helix of the desired length, the adjacent turns are preferably compressed axially in the manner shown in FIGURE 5. As illustrated in this figure, the turns which lie around the sleeve 18 are engaged at their opposite ends by annular plates 19 which may be drawn together axially by bolts 21 to press the turns of the conductor and insulating material tightly against each other.

While the turns of the coil are held in compressed condition a resinous plastic binder, such as an epoxy resin, is applied thereto. This may be done by brushing, spraying, dipping or in any other desired manner to provide an insulating covering over the conductor and to bind the turns of the conductor together. As will be seen in FIGURES 2 and 3, the resinous material indicated at 22 will flow into the open slots 17 to penetrate the full thickness of the coil. Preferably the material is applied in sufficient quantity to cover the outer surfaces of the conductor with a coating approximately one-eighth inch in thickness, although this is not critical. The resin may then be cured either by the application of heat or by air curing, depending upon the particular resin employed. When cured, the resin will adhere to the surfaces of the conductor and of the insulating material to secure them rigidly together in a unitary assembly. It will be noted that in addition to flowing into the slots 17, resin will flow to some extent between the surfaces of the conductor and the insulating material to form a very tight bond resulting in a rigid assembly.

After curing of the resin, the coil may be lined or enclosed in any other desired manner, as is known in the art, for mounting in apparatus such as a billet heater and may be used in the normal way. However, due to the fact that the turns of the coil are rigidly secured vibration of the coil turns in response to the application of

power thereto is minimized and a very efficient construction results which is at the time relatively easy to form.

While one embodiment of the invention has been shown and described herein, it will be understood that it is illustrative only and not to be taken as a definition of the scope of the invention, reference being had for this purpose to the appended claims.

What is claimed is:

1. An induction coil comprising a conductor wound into a helix with adjacent turns spaced apart and an insulating strip L-shaped in cross section helically interwound with the conductor with one flange of the strip lying radially within and contacting the inner surface of the conductor and defining a tubular liner therefor and the other flange extending radially between the turns of the conductor, said other flange being split radially at spaced points in the length of the strip.

2. An induction coil comprising a conductor wound into a helix with adjacent turns spaced apart and an insulating strip L-shaped in cross section helically interwound with the conductor with one flange of the strip

lying radially within and contacting the inner surface of the conductor and defining a tubular liner therefor and the other flange extending radially between the turns of the conductor, said other flange being split radially at spaced points in the length of the strip, the splits in the other end opening into V-shaped slots due to bending of the insulating strip, and a filler of plastic insulating material filling the slots.

3. The coil of claim 2 in which the filler is bonded to the conductor and insulating strips to secure them together in a unitary assembly.
